UNITED STATES PATENT OFFICE.

JOHN A. TOOMEY, OF LOS ANGELES, CALIFORNIA.

INTERNAL-COMBUSTION ENGINE.

1,304,629.

Specification of Letters Patent. Patented May 27, 1919.

Application filed October 29, 1917. Serial No. 199,060.

To all whom it may concern:

Be it known that I, JOHN A. TOOMEY, a citizen of the United States, residing at Los Angeles, in the State of California, have invented a new and useful Internal-Combustion Engine, of which the following is a specification.

My invention relates to internal combustion engines of the four cycle type, and the 10 objects of my invention are,

First, to provide a means for increasing or lessening the compression under which the charge is exploded, thereby increasing or decreasing the power of the engine,

Second, to provide a means for carbureting that will vary the mixture to correspond with the compression being used.

Third, to provide a means for effectually scavenging the explosion cylinders.

Fourth, to provide a suitable valve mechanism.

Fifth, to provide an effective lubrication and cooling system for this mechanism.

I attain these objects by the mechanism 25 illustrated in the accompanying drawings, in which—

Figure 1 is a vertical cross section of the engine.

Fig. 2 is a plan and sectional view of the 30 engine at certain designated sections.

Fig. 3 is a plan view of the intake manifold showing the compression control device and the carbureting device.

Fig. 4 is a sectional view of the valve 35 mechanism.

Fig. 5 is a sectional view of the carbureting device.

Fig. 6 is a sectional view of the device 40 controlling the lubricating and cooling system.

Similar letters and figures refer to similar parts throughout the several views.

The engine will be of four sets of cylinders, each set consisting of two superimposed cylinders A and B, having a differential area, a differential piston P, reciprocating therein, having the rod R connecting with the crank C, the cylinder A is surrounded by the jacket J in which will be the cooling 45 medium which in this engine will be a lu-

bricating oil as will be further described. The engine may follow any approved plan without varying the features of my invention and all parts of a modern internal combustion engine not specifically mentioned are 55 intended to be used and are considered to be and are claimed as a part of the invention.

A is the explosion cylinder and B is an air pump and compression cylinder which for the purpose of this invention should be approximately twice the cubic volume of cylinder A. The cylinder B has an automatic intake valve 1 for the admission of air which opens by suction and is closed by a spring. The cylinders A and B are connected by the bypass 2 for the purpose of conveying air from B into A during the scavenging stroke of the piston.

The manifold 3 connects with cylinder B of each set of cylinders and has a spring 70 valve 4 closing each cylinder so that air may pass from each cylinder B into the manifold but no air can pass from the manifold into the cylinder B. The manifold 3 also connects with the cylinder A of each set, the 75 connection being controlled by a valve mechanism to be further described, the construction being designed so that the air in cylinder B of that set of cylinders which are on the compression stroke will be diverted via the 80 manifold into the cylinder A of that set of cylinders which are on the suction stroke. The manifold 3 and all connections are air tight and made to retain air under pressure. The plan being to have the cubic volume of cylinder B greater than that of cylinder A, in order that the quantity of air transferred from B into A will exceed the capacity of A and result in an accumulated pressure of 85 air in the cylinders A and B and in the manifold 3. What this pressure will be is regulated by the valve 5 which is made part of the manifold 3, as shown in Fig. 3. The valve 5 is pivoted at the end of the lever 6, which is pivoted in the rigid brace 7. Parallel with the lever 6 is the lever 8 which is pivoted in the rigid brace 9 and is held and tensioned by the spring 10. Between the levers 6 and 8 is the sliding block 11 which transmits the tension of the spring 10 to the 90 95 100

lever 6 and holds the valve 5 closed. The block 11 is operated by the lever 12 and the rod 14 and may be moved backward and forward on the lever 8 to vary the leverage existing between the levers 6 and 8, in this manner changing the tension which the spring 10 exerts on the valve 5 and thereby controlling the air pressure which will accumulate in the manifold and in the cylinders A and B. The valve 5 allowing air to escape when the pressure exceeds the tension of the spring 10 exerted through the lever 8, the block 11 and the lever 6 upon the valve 5.

15 The manifold 3 has the branch 31 at right angles with it and divides into the arms 32 and 33, which convey the air into the explosion cylinders, terminating in the port 15 of each cylinder A. For the purpose of carbureting the air passing from the cylinder B into cylinder A the opening of the manifold 3 into the branch 31 is closed by a valve 18 which is tensioned by the springs 19 and 20 which hold the valve closed so that the air 25 passing through the manifold will force the valve upward. The valve 18 consists of a cast frame fitted to the valve seat and covered with a fine wire gauze 30. The stem 21 being rigid with the frame and hollow 30 extends into the tube 22 which is cast with or made a part of the tubular casting 23 which forms the base and has a pipe 24 connecting with the fuel supply tank 25. The nut 26 bolts the casting 23 to the manifold 3.

35 The lower end of the stem 21 is shaped and closed by the ball valve 27 and the opening between the tube 22 and the casting 23 is also shaped and closed by a ball valve 28. The open end of the tube 22 is closed by a packing case 29 through which the stem 21 passes. The open end of the stem 21 is closed by a movable rod 34 extending within the hollow stem and having a flared head whose object is to diffuse or spray the fuel 45 over the gauze 30.

The mechanism above described constitutes a fuel pump; the air lifting the valve 18 from its seat and the springs 19 and 20 drawing it back when the air pressure is relieved, and thereby pumping the fuel from the supply tank 25 and diffusing it upon the gauze 30. The force of the air in lifting the valve 18 will force part of the air through the gauze so that it will take up the fuel and carry it into the cylinder A thereby carbureting the air in the cylinder. The lift of the valve 18 is controlled by a bell crank 35 pivoted above the valve 18 within the branch 31. The crank 35 is connected with 50 the lever 12 by the rod 36 which has the turnbuckle 37 for adjustment, so that as the lever 12 is moved to vary the compression as before described, the bell crank 35 is moved and allows the valve 18 to lift a

greater or less degree and to pump a greater or less quantity of fuel on to the gauze 30 thereby giving a definite quantity of fuel to a definite volume of air. It being understood that the pump described is accurately constructed and lifting a definite quantity of fuel for each fraction of an inch of lift given the valve 18.

The cylinder A has the intake port 15, the by-pass port 16 and the exhaust port 17, all of which are located at the outer end of the cylinder and spaced so as to be controlled by the rotary valve 40 which has the ports 401 and 402. The valve 40 is an inverted cup and completely fills the end of the cylinder A. For the purpose of closing the cylinder A and protecting the valve 40 from the force of the explosion I use the head piece 41 which is inserted within the cylinder and has an extension 42 extending out of the cylinder and through the top casting 43 which forms the top for the cylinder casting. The outer end of the extension 42 has a screw thread 421, on which turns the nut 44 as a means for adjusting the position of the head piece 41 and the valve 40 and giving 90 a correct coincidence of the ports 15, 16, 17 of the cylinder casting with the ports 401 and 402 of the valve 40 and 151—161 and 171 of the head piece 41.

The force of the explosion upon the head piece 41 is carried by the cap 48 and the bolts 45 and 45 to the plate 46 which is bolted to the main cylinder casting and relieves the valve 40 of all pressure except the side pressure at the ports 151, 161 and 171.

The plate 46 is common to all the cylinders and is bolted to the main casting A being cut away to allow the valve 40 and the extension 42 to pass through, it forms a bearing for the valve 40 which is ground to a perfect fit with the head piece 41, the cylinder A and the plate 46.

The valve 40 has a spur gear 47 attached to it and is driven from the crank shaft by the worm gears 47 and 49. The detail of the connection with the crank shaft not being shown as this may follow any approved design.

The head piece 41 has the packing rings 50 to seal the cylinder under pressure and 115 is recessed and tapered to allow the spark plug 51 to be properly placed.

Because the mechanism of the valve requires that it be properly lubricated and because of its being directly exposed to the heat of the explosion it is proposed to use a lubricating oil as the cooling medium of this engine. I therefore will fill the jacket J and the head casting 43 with lubricating oil, the plate 46 being cut away at 52 to allow a free circulation. The cooling and lubricating medium may be kept separate from the lubricating system of the engine 125

and a separate pump and radiator used if desired. I have designed to use only one system and for the purpose of radiation and cooling of the oil have placed radiating fins 5 on the pan CC which forms the oil sump of the engine. The oil pump 61 is directly connected to the pan CC by the connection 63 and is designed to pump the oil under pressure so as to force the oil via the tube 10 64 to all parts of the engine that need forced lubrication. The amount of pressure used being controlled by the valve 65 which may be adjusted by the screw piece 66 releasing or compressing the spring 67 against the 15 valve 65.

When the pressure exceeds the tension of the spring the oil lifts the valve 65 and passes via the connection 68 into the jacket J. The jacket J is provided with an over-flow pipe 167 which extends into the cap 69 and carries the excess of oil back to the oil-sump CC. The casting 43 having the cap piece 69 and the vent 70 to allow for the accumulation and escape of any gas that may 25 form from the oil.

The foregoing valve system may be varied and any suitable valve mechanism may be used. I wish here to point out that the cylinder B may be eliminated and the crank 30 case divided to form a compression chamber for each cylinder. The reciprocating piston drawing the air into and forcing it out of the crank case in place of the described cylinder B. The manifold, the control element, and the other features of the engine 35 remaining the same.

Having described the mechanism the operation will be as follows: In every two revolutions of the crank each set of cylinders 40 will have a suction, compression, explosion and exhaust stroke. If therefore the piston of any set of cylinders is on the downward stroke, air will be drawn into cylinder B through the valve 1, and if this be the explosion stroke of the cylinder A of that set of cylinders, at the end of the downward stroke the valve 40 will open, first the exhaust port 17 and then the by-pass port 16 and on the upward stroke of the piston the air in cylinder B will pass via the by-pass 2 and the port 16 into the cylinder A and out via the exhaust port 17 scavenging cylinder A of all burnt gas. On the second downward stroke of the piston, air is again drawn into B 55 through the valve 1 and this being the compression stroke the by-pass and all ports are closed by the valve 40 and the air is forced to pass through the valve 4 into the manifold 3 and lifting the valve 18 it will be carried by passing through the gauze 30 and will pass into the cylinder A of that set of cylinders which are on the suction stroke, the valve 40 of that set having the port 15

As before stated the cubic volume of cylinder B exceeds that of cylinder A and the volume of air transferred into cylinder A results in a compression of air in cylinder A. What this pressure will be depends upon the valve 5 which opens when the air 65 pressure exceeds the tension of the spring 10 and thus regulates the pressure. Compression and explosion of the gas follows and the cycle is repeated for each set of cylinders.

It should be noted that the block 11 may 70 be moved to the point α when all tension on the valve 5 being removed the valve would open and the engine would be operated by suction of the piston only. This gives a 75 range of compression varying from a low 80 standard up to and limited by one that would cause a premature ignition of the charge. The compression space of cylinder A being so designed that the suction position of the valve 5 would give a compression as low as desired but which may be increased by control of the valve 5 to the highest practical compression, gaining thereby 85 the advantages of an increase of power due to exploding the charge under high compression and having combined with it the increased power due to increasing the volume of gas exploded, for it will be noted that the increase of compression is obtained by increasing the volume of gas to be compressed, applying to an internal combustion engine the principle of a progressive compression and giving to it a range of power 90 similar to a steam engine.

I am aware that certain parts and details 100 of my engine have been in use before and are here claimed only in combination with the improvements I have made and which I claim to be—

1. In an apparatus of the kind described, 105 an internal combustion engine having four sets of differential area cylinders A and B, each cylinder A having the ports 15, 16 and 17, the fixed head piece 41 in which are the ports 151, 161, 171 to register with the ports 110 15, 16, 17 of the cylinder, a rotary valve 40 in which are the ports 401 and 402 to register with the ports 15, 16, 17 and the ports 151, 161, 171 and control the intake and exhaust of gas and air, means for operating 115 the valve 40 mechanically from the crank shaft, each cylinder B having the valve 1 the by-pass 2 and the valve 4 for the intake and exhaust of air, a differential piston P reciprocative in each set of cylinders, a connecting rod R for each piston, a crank shaft S, a manifold 3 connecting all cylinders B, the branch 31 and the arms 32 and 33 to convey air from the cylinder B to the ports 15 of each cylinder A, all in combination with the 120 valve 5, the levers 6 and 8, the sliding block 11, the spring 10 and means for moving the block 11 to vary the tension of the spring 125

10 upon the valve 5 and thereby control the movement of air from cylinder B into cylinder A substantially as described.

2. In an apparatus of the kind described, 5 an internal combustion engine having four sets of differential area cylinders A and B, each cylinder A having the ports 15, 16, 17, the fixed head piece 41 in which are the ports 151, 161, 171 to register with the ports of the 10 cylinders, the rotary valve 40 in which are the ports 401 and 402 to register with the ports 15, 16, 17 and 151, 161, 171 and control the intake and exhaust of gas and air, means for operating the valve 40 mechanically 15 from the crank shaft, each cylinder B having the valve 1, the by-pass 2 and valve 4 for the intake and exhaust of air, a differential piston P reciprocating in each set of cylinders, a connecting rod R for each piston, a 20 crank shaft S, a manifold 3 connecting all of the cylinders B, the branch 31 and arms 32 and 33 for conveying the air from the cylinders B to the port 15 of each cylinder A, the valve 5, the pivoted levers 6 and 8, the sliding block 11, the spring 10, means for sliding the block 11 and to vary the tension of the spring 10 and thereby control the valve 5, all in combination with the valve 18, the springs 19 and 20, the gauze 30, the stem 21, 25 the hollow tube 22, the casting 23, the piping 24, the fuel supply tank 25, the nut 26, the ball valves 27 and 28, the packing case 29, the rod 34, as a means for carbureting the air passing from the cylinders B into cylinders A, substantially as described.
3. In an apparatus of the kind described, 30 an internal combustion engine having four sets of differential area cylinders A and B, each cylinder A having the ports 15, 16, 17, the fixed head piece 41 in which are the ports 151, 161, 171 to register with the ports 15, 16, 17 of the cylinders, the rotary valve 40 in which are the ports 401, 402 to register with the ports 15, 16, 17 and 151, 161, 171 and control the intake and exhaust of gas and air, means for operating the valve 40 mechanically from the crank shaft, each cylinder B having the valve 1, the by-pass 2 and the valve 4 for the intake and exhaust of air, a differential area piston P reciprocating in each set of cylinders, a connecting rod R for each piston, a crank shaft S, a manifold 3 connecting all of the cylinders B, the branch 31 and the arms 32 and 33 for conveying air from the cylinders B to the port 15 of each cylinder A, the valve 5, the pivoted levers 6 and 8, the spring 10, the sliding block 11, the valve 18, the springs 19 and 20, the gauze 30, the stem 21, the hollow tube 22, the casting 23, the piping 24, the fuel tank 25, the nut 26, the ball valves 27 and 28, the packing case 29, the rod 34, all in combination with the bell crank 35, the rod 36, the turnbuckle 37, the lever

12 and the rod 14 as a means for carbureting the cylinders A and adjusting the volume of gas to the varying volume of air substantially as described.

4. In an internal combustion engine, having in combination explosion cylinders and air compressors, a manifold connecting all of said air compressors, automatic valves in each air compressor for the intake of air into said air compressor and the exhaust of said air into the manifold, reciprocating pistons in said explosion cylinders and air compressors, a crank shaft, connecting rods for each piston to the crank shaft, an explosion space formed in each explosion cylinder between the piston and the cylinder head, a branch from said manifold having extensions connecting it with the said explosion space in each cylinder, a carbureting device located in the said branch designed to carburet the air passing from the manifold into the explosion space, valves in each explosion cylinder, operated mechanically from the crank shaft, for the intake of carbureted air from the manifold, and the exhaust of burnt gas from the cylinder, means for the compression and explosion of said air in the cylinder, said air compressors designed to create an air pressure in the manifold and explosion cylinders, an air control element located in the manifold, designed to operate by said air pressure and divert part of the said air and prevent it from entering the carburetor and explosion cylinder, and means for changing said air control element and thereby controlling the volume of carbureted air entering said explosion space and the compression created therein, substantially as described.

5. In an internal combustion engine, having in combination explosion cylinders and air compressors, a manifold connecting all of said air compressors, automatic valves in each air compressor for the intake of air into said air compressor and the exhaust of the air into the manifold, reciprocating pistons in said explosion cylinders and air compressors, a crank shaft, connecting rods for each piston to the crank shaft, an explosion space formed in each explosion cylinder, between the piston and the cylinder head, a branch from said manifold having extensions connecting it with the said explosion space in each cylinder, a carbureting device located in said branch designed to carburet the air passing from the manifold into the explosion space, valves in each explosion cylinder, operated mechanically from the crank shaft, for the intake of carbureted air from the manifold, and the exhaust of burnt gas from the cylinder, means for the compression and explosion of said air in the cylinder, said air compressors designed to create an air pressure in the manifold and

explosion cylinders, an air control element located in the manifold, designed to operate by said air pressure and divert part of said air and prevent it from entering the car-

5 bureter and the explosion cylinder, means for changing said air control element, means for changing said carbureting device, and means jointly operating the said air control

and carbureter control and thereby control the mixture of air and gas entering the explosion cylinder and the compression created therein, substantially as described. 10
